Primary Examiner—Robin V Webster(74) *Attorney, Agent, or Firm*—Wesley W. Muller(57) **CLAIM**

The ornamental design for a wand, as shown and described.

DESCRIPTION

FIG. 1 is a perspective view of a wand according to the present invention;

FIG. 2 is a left side view of the wand of FIG. 1;

FIG. 3 is a right side view of the wand of FIG. 1;

FIG. 4 is a top view of the wand of FIG. 1;

FIG. 5 is a bottom view of the wand of FIG. 1;

FIG. 6 is an elevated front view of the wand of FIG. 1;

FIG. 7 is an elevated rear view of the wand of FIG. 1; and,

FIG. 8 is an additional left side view of the wand.

The broken line showing in FIG. 8 is included for the purpose of illustrating and forms no part of the claimed design.
